(57) **CLAIM**

The ornamental design for an optical waveguide spool, as shown and described.

DESCRIPTION

FIG. 1 is a top perspective view of an optical waveguide spool showing our new design;

FIG. 2 is a top plan view thereof;

FIG. 3 is a side elevational view thereof, having three other sides being a mirror image;

FIG. 4 is a top perspective view thereof;

FIG. 5 is a bottom plan view thereof;

FIG. 6 is a right side elevational view of the design shown in FIG. 5;

FIG. 7 is a front elevational view thereof;

FIG. 8 is a left side elevational view thereof; and,

FIG. 9 is a rear elevational view thereof.

The broken line showing the optical waveguide spool in FIGS. 1 through 4 is for illustrative purposes only and forms no part of the claimed invention.
